UNITED STATES PATENT OFFICE.

FREDERICK STITZEL, OF LOUISVILLE, KENTUCKY, ASSIGNOR OF ONE-HALF
TO ADOLPH REUTLINGER, OF SAME PLACE.

ROTARY STEAM-ENGINE.

SPECIFICATION forming part of Letters Patent No. 297,091, dated April 15, 1884.

Application filed July 24, 1883. (No model.)

To all whom it may concern:

Be it known that I, FREDERICK STITZEL, a citizen of the United States, residing at Louisville, in the county of Jefferson and State of Kentucky, have invented certain new and useful Improvements in Rotary Steam-Engines, of which the following is a full, clear, and exact description.

This invention is in the nature of improvements in rotary steam engines and pumps, and has special reference to the simplification of the construction and operation of such apparatus.

The invention consists of a steam-engine the casing of which forms the cylinder, and contains a rotary piston divided centrally into two independent chambers having openings into the cylinder for the live and exhaust steam, respectively, an axial inlet to the live-steam chamber, and an axial outlet for the exhaust-chamber, combined with a working-head on said piston co-operating with two abutments in the cylinder, which divide the cylinder into live and exhaust steam chambers, all as I shall now proceed to set forth and claim.

In the accompanying drawings, in the several figures of which like parts are similarly designated, Figure 1 is an elevation of the interior of my engine with the proximate head of the cylinder or casing removed. Fig. 2 is a central vertical cross-section of the same. Fig. 3 is a top plan view, with a part of the casing broken away to show one of the abutments, and also showing the steam-supply pipe for the operation of said abutment. Fig. 4 is an edge elevation of the piston detached, and Fig. 5 a top plan view of said piston with the packing removed.

The casing *a*, provided with a suitable base, has an annular body, *b*, and discous heads *c c*, bolted steam-tight to said body, the whole forming a steam-cylinder, and I shall herein-after designate the same by the term "steam-cylinder," or simply "cylinder."

The heads *c c* have upright tubular portions *d d*, constituting, by suitable connections, an inlet and outlet for the steam, and so serving, according to the direction of rotation of

the piston, as will hereinafter appear. These 50 inlet and outlet tubes open into the cylinder at about the center thereof, and terminate in tubular bosses *e e*, which serve as boxes for the shaft *f* of the piston *g*. The shaft is fitted steam-tight in these boxes by suitable packing or stuffing boxes. The holes *h h* in the heads of the cylinder are enough larger than the shaft to form, inlet and outlet ports for the steam-cylinder in communication with the tubes *d d*.

The piston *g* is a flat circular casting, cored out into two chambers, *i i'*, separated by a central vertical partition, *j*, and provided with an internal recessed hub, *k*, whereby it is fitted upon its shaft *f*, so as to rotate said shaft to 65 transmit power from the engine. The piston is of such smaller diameter than the cylinder as to leave an annular chamber, *l*, between the two, and its faces are provided with annular packings *m n*, forming steam-tight joints with 70 the heads of the cylinder. The packing-ring *m* surrounds the inlet and outlet to the cylinder, and the ring *n* is arranged near or at the edge of the piston. Depressions *o o* in the faces of the piston, and connecting-tubes *p* 75 extending transversely through the piston, serve as steam-balancing mediums for the piston, preventing friction, or reducing it to a minimum, and neutralizing leakage.

The piston is provided with a piston-head 80 proper, *q*, having its transverse edge and sides grooved, with packing-strips *r* inserted in said grooves, so that said head has a superficial area of an extent coincident with the width and height of the steam-chamber *l*, and fitting 85 steam-tight in said chamber. The grooves in the head *q* are shown at *q'* in Fig. 5.

The steam-chamber *l* is divided by abutments *s s'*, arranged to work in boxes *t t'* on the cylinder. These abutments are normally held in 90 contact with the piston *g* by pistons *u u'*, arranged in cylinders *v v'* normally charged with steam by a pipe, *w*, which may receive its steam-supply from any suitable source—as, for instance, the live steam from the boiler 95 of the engine—and the quantity of steam used need be very small.

The head *q* of the piston is provided with a

port, r' , (see dotted lines, Figs. 1 and 2, and full lines, Figs. 4 and 5,) whereby communication is established between the steam-chamber i of the piston and the annular chamber l of the cylinder, and the piston g is provided with a port, g' , (see dotted lines, Fig. 2, and full lines, Figs. 4 and 5,) whereby communication is established between the other chamber, i' , of the piston and the annular chamber l of the cylinder. There is thus no direct communication between the chambers i and i' , and both open into the annular chamber l .

The continuous longitudinal dotted lines in Figs. 4 and 5 represent the location of the partition j .

As an auxiliary of the depressions o and pipes p in balancing the piston and maintaining an equilibrium of steam-pressure, I may make small holes o' through said depressions into the chamber i' to insure sufficient and equal steam-pressure. So, also, to insure the efficiency of the packing-rings and strips, there may be beneath them openings p' from their grooves into the piston, whereby they will be forced out against the walls of the cylinder by steam.

The piston will be so made or cast as that the weight of its head will be compensated for.

The operation of my engine is as follows: As exhaust-port g' is located and rotating in advance of head q , it exhausts before abutment s' . Then it passes under and past abutment s' , exhausting behind said abutment. The curvilinear surface of head q now comes in contact with the abutment s' , and as there is no pressure on any face of said abutment it will be pushed back by head q with but the friction of the weight of the abutment on the boxes or guides and the pressure of the little piston u' to overcome. The head q now passes under abutment s' , and it is immediately restored to its former seat. Exhaust-port g' then passes under and beyond abutment s , exhausting the upper half of the cylinder l , thereby instantly throwing the pressure on the lower surface of the abutment s' . The abutment s having been relieved from its pressure on all sides, is now reached by head q , pushed back and passed by same and seated again by the piston u . The exhaust-port g' then approaches and passes under and beyond abutment s , exhausting the lower half of the cylinder l , thereby throwing instantly the pressure on the upper surface of abutment s , and the abutment s' is in due time passed by head q .

It will be seen by the action of the several parts of this engine in running or rotating, the exhaust-port g' is always exhausting in advance of head q , and that the induction-port r' is always admitting live steam behind head q , that valves s and s' have alternately the pressure of fixed resistance to bear—viz., abutment s on its upper surface and valve s' on its lower surface.

Referring to Fig. 1, and considering the piston rotating or running, the resistance is on

the lower side of abutment s' , because exhaust-port g' has just passed under and beyond it, exhausting upper cylinder, l . On the drawings, the piston-head q is at its highest point, 70 and cylinder l is filled with live steam from the lower surface of s' to the highest point of head q on port r' side. There is no pressure on abutment s , because from the lower surface of abutment s' to top of head q , port r' , the 75 cylinder is filled with equal pressure, and consequently abutment s is pressed equally from all sides. Now, port g' will pass under and beyond abutment s' , exhausting the lower half of cylinder, whereby the pressure will be instantly thrown on top of abutment s . The 80 functions of these abutments are therefore to take the pressure from each other to allow head q to pass them. Say, abutment s holds the pressure to allow abutment s' to be passed 85 and have sufficient time to seat true and quietly, then abutment s' takes the pressure to allow abutment s to do the same. There is no pressure whatever on these abutments when they slide backward and forward. The operation 90 takes place twice in one revolution. There is no dead-center, no variation of pressure area on head q and on abutments s and s' , as the pressure is all on one abutment while the other is being passed. The ports g' and r' are arranged on opposite sides of the head, as is obvious, and their relative location is indicated in Fig. 5, and also in Fig. 4, a part of the piston being broken away in the latter figure to more fully show the port g' . From 95 this it will be seen that after the first exhaust, the parts of the chamber l , on opposite sides of the abutments s and s' , are alternately live and exhaust steam chambers, owing to which of the ports r' and g' are therein, and one or the 100 other of said ports is in either one or the other of said chambers at all times during the admission of live steam. The steam acting through pistons u and u' seats the abutments s and s' and never escapes from, but plays back and 105 forth in its pipe. The travel of the exhaust-steam is through the port g' , chamber i' , and out around the shaft and tube on the right-hand side of Fig. 2.

The inlet of the steam may be made as small 110 as desired, so as to avoid expansion, and the whole regulated by a governor.

This engine can easily be made reversible, but as one means for accomplishing this will form the subject-matter of a future application, I will not now detail the same.

A modification of the mechanism herein shown and described I have applied in a pressure water-meter, as may be seen by reference to my concurrent application for a patent 125 therefor, Serial No. 101,748, and such application thereof I do not here claim.

What I claim is—

1. A steam-engine the casing of which forms the steam-cylinder, the rotary piston 130 divided centrally into two independent chambers having openings into the cylinder for

the live and exhaust steam, respectively, a solid hub and shaft for said piston, the axial inlet for the live steam, and the axial outlet for the exhaust-steam, combined with the working-head on said piston co-operating with two abutments in the cylinder, which divide the cylinder into live and exhaust steam chambers, all constructed and arranged to operate substantially as and for the purpose set forth.

10 2. The combination, with the cylinder and piston, of abutments s s' , normally seated against the piston and provided with operating-pistons, and a normally and constantly charged steam-pipe connecting the two, substantially as and for the purpose described.

15 3. The rotary piston having separated non-

communicating induction and eduction ports or chambers, facial depressions, and transverse tubes connecting such depressions to equalize the pressure upon the said piston within its 20 casing or cylinder, substantially as set forth.

4. The combination, with the cylinder and the two-chambered rotary piston therein, of the facial packing-rings in said piston, and steam-passages behind them, substantially as 25 and for the purpose specified.

In testimony whereof I have hereunto set my hand this 21st day of July, A. D. 1883.

FREDERICK STITZEL.
